UNITED STATES PATENT OFFICE.

DE VER H. WARNER, OF BRIDGEPORT, CONNECTICUT.

DESIGN FOR A CORSET.

SPECIFICATION forming part of Design No. 28,086, dated December 21, 1897.

Application filed September 22, 1897. Serial No. 652,660. Term of patent 14 years.

To all whom it may concern:

Be it known that I, DE VER H. WARNER, a citizen of the United States, residing at Bridgeport, in the county of Fairfield and State of Connecticut, have invented and produced a new and useful Design for Corsets, of which the following is a specification, reference being had to the accompanying drawing, forming a part thereof.

10 In the accompanying drawing I have shown a view of one-half of a corset with the parts extended, showing the essential features of my new design embodied in a corset.

15 The characteristic or leading features of my new design consist in the corset herein shown provided with a zone or strip extended from top to bottom of the corset, a second zone or strip extending from the bottom of the corset at some distance from the first strip or zone 20 and approaching said zone near the top of the corset, and a tapering or wedge-shaped piece interposed between the two zones or strips and extending from their adjacent upper portions to the bottom of the corset.

25 Thus, in the drawing, A represents the body of the corset, comprising a front portion B,

a back portion C, and a middle or hip portion D. On the forward part of the hip portion D there is a zone or strip E, extending from the top to the bottom of the corset. On the rear part of the hip portion D there is a zone or strip F, extending from the bottom of the corset at a point some distance from the strip E toward and approaching said zone or strip E near the top of the corset. Between the 30 zones or strips E F a tapering or wedge-shaped portion G is interposed, the pointed part of the tapering portion being located at the adjacent upper portions of the strips E F and the tapering portion gradually expanding 35 until it reaches the bottom of the corset.

What I claim is—

The design for a corset substantially as shown and described.

In testimony whereof I have signed my 45 name to this specification in the presence of two subscribing witnesses.

DE VER H. WARNER.
